UNITED STATES PATENT OFFICE.

FRED A. JOHNSON, OF WOLVERTON, MINNESOTA.

BAG HOLDER.

Application filed May 26, 1925. Serial No. 33,004.

This invention relates to an improved bag holder for use in connection with a picking table, such as is employed in connection with a potato grader or the like.

5 The invention has more specific reference to a device adapted for use in connection with the table, wherein the same is provided at one end with a discharge opening, into which the potatoes are pushed and allowed 10 to drop into the bags placed beneath this opening.

The present invention relates in one instance to the placement in this discharge opening, of a pivotally mounted plate, which 15 serves as a chute, by means of which the graded potatoes may be diverted or shunted through one side or one half of the opening into a bag located therebeneath.

It follows that the invention permits the 20 use of two bags, one bag being filled at a time and removed, while the other bag is filled, that is, one bag is hung and filled, and while it is being removed, the other bag is filled, and while the latter is being removed, 25 the first bag has been replaced and is ready to be again filled. In this way, the operation is substantially continuous.

The invention is further characterized by 30 the presence of a plurality of suspension hooks, at least two of which are mounted upon spring pressed arms, moved outwardly in a manner to stretch or hold the mouth of the bag open, to facilitate insertion of the 35 potatoes.

35 Other features and advantages of the invention will become apparent from the following description and drawings.

In the accompanying drawing, forming a 40 part of this application, and in which like numerals are employed to designate like parts throughout the same:

45 Figure 1 is an inverted plan view of a grading table and bag holder constructed in accordance with the invention.

Figure 2 is an end elevation of the same.

Figure 3 is a fragmentary side elevation.

In the drawing, the reference character 1 designates the opposed vertical side walls of 50 a box at the ends of which is an end wall 2. The table proper is designated by the reference character 3, and it will be noted that the forward end 4 thereof terminates in a spaced relation from the end wall 2 from 55 the box to provide a substantially elongated discharge opening 5. It is beneath this open-

ing that the two bags are adapted to be hung so that the potatoes may be shunted into the open mouths of the same. In this connection, it should be noted that a rod 6 extends across the opening 5, and is connected with the end wall 2. This rod forms a fulcrum for a pivotally mounted swingable plate or the like 7, which functions as a chute. A handle 8 is connected to the intermediate portion of one edge of this plate, and this handle extends outwardly through an arcuate slot formed in the end wall 2 of the box. From Figure 2, it will be seen that a reinforcing plate 9 having a slot is 70 connected to the end wall and serves to render the structure more rigid. I would also direct attention to the fact that the table 3 is disposed on a plane, so that it is disposed above the upper end of the chute 7, when 75 the same is in either of its inclined positions, as shown in Figure 2. Thus, the potatoes can be literally shoved off of the table onto the chute, and shunted into the bag located between the uncovered portion of the opening 5. From Figure 2, it is clear that one corner of the bags are suspended from the hooks 10 formed on the downturned arms of the U-shaped member 11, fastened to the center of the end wall 2. 80

Observing Figure 1, it will be seen that a tube 12 is suspended, in any appropriate manner, on the bottom of the structure, and rods 13 telescope into the ends of this tube, being held in adjusted positions by cotter pins or the like 14. On the outer ends of the rods are hooks 15 for piercing the adjacent corners of the bag. At the center of the tube 12 are closely spaced hooks or the like 16, to which the inner opposed corners 95 of the two bags are connected. Novel means are employed for co-action with the remaining corners of the bags and for stretching the mouths of the bags open to facilitate the entrance of potatoes. 100

In carrying out this end, blocks 17 and 18 are fastened to the side walls 1. Pivoted upon each block 18 is a right angular tube 19, which carries an adjustable rod 20, at the free end of which is a hook 21. A 105 spring is mounted upon the block 18 and the free end of the extension 22 of the spring co-acts with the tube 19 to swing it outwardly in the direction indicated.

As before intimated, two bags are used. 110 These bags are placed beneath the two openings formed by the presence of the chute

7 in the relatively large opening 5. Opposed walls of the two bags are hooked on the hooks 10 and 16. Corresponding corners are connected to the hooks 15 and the remaining corners are connected to the hooks 21 on the swingable arms 20. These arms are pressed outwardly by the springs and the mouths of the bags are maintained wide open. Assuming that the chute is inclined to the left as indicated in Figure 2, the potatoes are pushed off of the table 3, onto the chute 7, and are diverted to the right into the bag on the right hand side. After this has been filled and while it is being removed, the handle 8 is grasped and the chute is swung to the opposite inclined position and the remaining bag is filled. While it is being filled, another empty bag is placed on the first named side.

Undoubtedly a careful consideration of the description in connection with the drawing, will enable persons skilled in the art to which the invention relates to obtain a clear understanding of the same. Therefore, a more lengthy description is thought unnecessary.

While the preferred embodiment of the invention has been shown and described, it is to be understood that minor changes coming within the field of invention claimed may be resorted to, if desired.

I claim:

1. In a structure of the class described, a table frame, bag holding means supported on said frame and including swingably

mounted hooks adjacent one end of the frame, a tube supported on said frame in spaced relation to said end, additional hooks slidably mounted in the ends of said tube, a fulcrum rod extending through said end of the frame and associated with said intermediate portion of said tube, a plate hingedly connected to said rod, and operating means for said plate extending through an opening in said frame. 45

2. In a structure of the class described, a table frame, a tube extending transversely across the bottom of the frame at a point inward of one end wall of the frame, stationary hooks on the intermediate portion 50 of the tube, additional hooks slidable in the ends of the tube, a fulcrum forming rod rotatably mounted in said end wall of the frame and in the bearing opening in the intermediate portion of said tube, a chute 55 forming plate in connection with said rod, and additional hooks carried by said frame.

3. In a structure of the class described, a supporting frame, a tube carried by said frame, pins connected to the central portion of the tube, hooks including shanks slidably mounted in the ends of said tubes, right angular tubular members swingably mounted on said frame, additional hooks adjustably mounted on said right angular members, and a U-shaped member mounted on one end wall of the frame and in alignment with the first named hooks. 60 65

In testimony whereof I affix my signature.
FRED A. JOHNSON.
